UNITED STATES PATENT OFFICE.

JACOB SCHOBEE GAINES AND MARTIN E. CREIGHTON, OF CAIRO, ILLINOIS.

CIRCUIT CLOSER.

Application filed March 31, 1922. Serial No. 548,458.

To all whom it may concern:

Be it known that we, JACOB SCHOBEE GAINES and MARTIN E. CREIGHTON, citizens of the United States, residing at Cairo, in the county of Alexander and State of Illinois, have invented new and useful Improvements in Circuit Closers, of which the following is a specification.

This invention relates to signals, and comprehend the provision of a mechanism adapted for use in conjunction with boilers, said mechanism being automatically operated at predetermined intervals to close an electric circuit.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:—

Figure 1 is a view in elevation of the invention.

Figure 2 is a view taken at right angles to Figure 1.

Figure 3 is a vertical sectional view through the device.

Figure 4 is a diagrammatic view.

Referring to the drawings in detail, 10 indicates a boiler which communicates with the water column 11, the latter being arranged in parallelism with the boiler in the usual well-known manner. This communication is established by the pipes 12 each of which is provided with a valve 14.

40 Journaled in suitable bearings 15 supported by the water column 11 are shafts 16 and 17 respectively. These shafts are mounted for partial rotation and each supports a disk 18, the latter being preferably of insulating material and supporting fixed contacts 18. Projecting from each of said shafts adjacent its disk is an arm 19, and slidably mounted upon this arm is a counter-bearing weight 20. The movements of the 50 shafts are alternately controlled by means of floats 21 arranged within the water column 11 adjacent the opposed ends thereof.

Each float is supported by a rod 22 which is secured to the adjacent shaft. The rise 55 and fall of these floats independently control the shafts with which they are associated,

so as to turn the shaft in either direction to make or break the circuit to operate the signal in a manner to be presently described. Supported by the water column 11 is a 60 shaft 24, which is arranged in parallelism with the rotatable shafts, and supports at its outer end a vertically disposed rod 26 which is arranged at a right angle to the shafts 16 and 17. Both ends of this rod terminate to provide bearings 27 which slidably receive stub shafts 28, the latter being held fixed relatively to the rod by means of set screws or the like 29. Each stub shaft carries an insulated disk 30, which is arranged in confronting relation to one of the disks above mentioned, and carried by each disk 30 is a fixed contact 31. Also supported by the fixed shaft 24 are conduits 32 through which the conducting wires are 70 passed, there being one of these wires 33 coupled to each of the fixed and movable contacts above referred to, and also leading to a switch 35 and the signals 36 and 37 respectively. It might be here stated that the signals 36 and 37 may be of any suitable construction and of any type signal, other than an audible signal which is herein shown as bells.

In practice, when the water is admitted to the water column 11 and reaches its high level within said boiler, the float at the upper end of said boiler is elevated, thereby partially rotating the adjacent shaft 16, with a consequent turning of the disk supported thereby, bringing the movable contact into engagement with the fixed contact and closing the circuit to sound the alarm or bell indicated at 36.

As illustrated in Figure 4, the current 95 flows from the source of supply 38 through the switch 35, to the contacts above mentioned, thence through the alarm 36 and returned by the wire 39 to the batteries or source of current 38. When the water in the column 11 falls to a predetermined level, it operates the float in the lower end of the boiler, turning the adjacent shaft to close the circuit in the manner above described in connection with the bell 36. The bells 100 36 and 37 are designed to provide different tones or sounds, so that the engineer or attendant will be able to determine at some remote point, conditions as they exist in the 105 boiler room.

While it is believed that from the foregoing description, the nature and advantages

of the invention will be readily apparent, we desire to have it understood that we do not limit ourselves to what is herein shown and described, and that such changes may be resorted to when desired as fall within the scope of what is claimed.

What we claim is:—

1. In combination with a reservoir and a plurality of floats pivotally mounted there-in, a rock shaft extending from the float, a disk carried by the end of the rock shaft, contact elements carried by the disk, a vertical bracket member supported adjacent the reservoir, axially adjustable element carried

by the ends of the bracket member, a disk 15 carried by each of the axially adjustable elements, and contact elements extending from the disk and adapted to be engaged by the first mentioned contacts, the contacts in the last mentioned disks being adapted to be 20 connected with the source of electrical energy which in turn is connected with a signal.

In testimony whereof we affix our signatures.

JACOB SCHOBEE GAINES.
MARTIN E. CREIGHTON.
